Term of patent 14 years

(Cl. D4—2)

Fig. 1.

Fig. 5.

Fig. 2.

Fig. 3.

Fig. 4.

FIG. 1 is a top plan view of a wash stand embodying my new design;

FIG. 2 is a front elevational view thereof;

FIG. 3 is a fragmentary side elevational view thereof, with a portion of the side panel of the base broken away to show the slope of the two triangular rear panels illustrated in FIG. 4, and with portions of the details shown in broken lines omitted for convenience of illustration.

FIG. 4 is a rear elevational view thereof; and

FIG. 5 is a bottom plan view thereof, the broken lines being omitted for convenience of illustration.

The side not shown is substantially the same as the side shown.

The dominant features of my design reside in the portions shown in full lines.

We claim:

The ornamental design for a wash stand, as shown and described.
